UNITED STATES PATENT OFFICE.

FREDERIC WILLIAM CHAMIER AND WILLIAM CURTIS, OF HYDE PARK, LONDON,
ENGLAND, ASSIGNEES TO C. P. G. COMPANY, LIMITED, OF LONDON, ENGLAND.

HAND-GRENADE AND THE LIKE.

1,303,163.

Specification of Letters Patent.

Patented May 6, 1919.

Application filed November 27, 1916. Serial No. 133,666.

To all whom it may concern:

Be it known that we, FREDERIC WILLIAM CHAMIER and WILLIAM CURTIS, both subjects of the King of Great Britain, residing at 63 Queensborough Terrace, Hyde Park, in the county of London, England, have invented certain new and useful Improvements in or Relating to Hand-Grenades and the like, of which the following

10 is a specification.

This invention relates to hand grenades and trench mortar bombs of the percussion or impact type as distinct from those provided with time fuses.

15 According to the invention the firing mechanism of the grenade or bomb (hereinafter termed "grenade") is prevented from operating to effect the explosion of the bursting charge, by a displaceable ball or member which is normally supported centrally in a fixed position but upon impact of the grenade is rendered free and becomes displaced to release the firing mechanism, a suitable safety device (which may be in the form of 20 a displaceable cage surrounding the said loose ball or member) being preferably provided to prevent the ball from becoming free until the grenade has left the hand of the thrower or has been discharged from a 25 throwing device.

30 In order that the said invention may be clearly understood and readily carried into effect the same will now be described more fully with reference to the accompanying drawings which shows the preferred embodiment of the invention and in which:—

Figure 1 is a sectional elevation showing the parts in their normal position.

Fig. 2 is a sectional elevation illustrating 40 the approximate position assumed by the parts immediately the grenade has been thrown.

Fig. 3 is a sectional elevation showing the approximate position assumed by the parts 45 after impact with the object aimed at and at the moment of firing.

1 is the body of the grenade which is of the usual construction and configuration. 2 is a centering disk, and 3 is a hollow closure 50 plug which is screwed into an opening 4 at the base of the grenade. The disk 2 is formed with a central opening 5, and between the said opening 5 and an opening 6 in the top of the grenade is located a center piece 7 in the form of a tube having an 55 enlarged bulbous center part 7'. 11 is the

displaceable member in the form of a ball, which is normally held between supporting members 12 and 17. Slidably mounted within the upper part of the center piece 7 is a 60 displaceable hollow safety cage 8, having the form of a hollow piston or plunger provided at its upper end with a conical part 9 and at its lower end with a number of 65 depending arms 10, which normally surround the ball 11. Within the safety cage 8 is located the member 12 in the form of a cylinder or plunger having a recessed upper part 13 and a lower part 14 of trunco-conical formation formed with a slightly indented end 15 which engages the adjacent 70 surface of the ball 11. The part 12 may either be fixed or movable. In the embodiment shown the part 12 is locked against movement by indenting with a center punch 75 a part 7² of the center piece 7 into the part 12. Located between the recessed upper part 13 of the part 12 and the inner end of the hollow cage 8 is a helical compression 80 spring 16. Slidably mounted within the lower part of the center piece 7 is the plunger 17 the upper end 18 of which is of trunco-conical formation and has a slightly indented end 19 which engages closely the 85 adjacent surface of the ball 11. The lower part of the plunger 17 is provided with a central boss or extension 20 over which is passed a washer 21 and around which is located a helical compression spring 22 one 90 end of which bears on the said washer and the other end of which rests on the hollow closure plug 3. The plunger 17 is formed with a longitudinal slot 23 within the lower part of which is secured a detonator 24. Provided on the center piece 7 is a spring 95 collar 25 which is sprung into position around the center piece 7 and which comprises a split ring having a bent part 26 forming a striker which extends through an opening 27 in the center piece 7 into the 100 aforesaid longitudinal slot 23. 28 is a safety lever similar to that forming part of certain known types of hand grenades the pivot or fulcrum 29 being disposed at the opposite side of the axis of the grenade to that occupied by the major portion of the lever 28. The safety lever 28 is normally maintained in its inoperative position by the usual detachable pin 30 and finger ring 31. The grenade has the usual inner chamber 110 32 containing the bursting charge and a filling hole 33 closed by a removable plug 34.

It will be understood that the cavity formed by the bulbous center part 7' is of sufficient size to enable the ball 11 to assume a position in which it will offer no impediment to the firing movement of the plunger 17 and that the depending arms 10 normally surround the ball and prevent its displacement. When, however, the pin 30 is withdrawn and the grenade leaves the hand of the thrower or is discharged from a throwing device, the safety lever 28 is released and moves about its fulcrum 29 under the influence of the upward pressure of the spring pressed part 9 until the hand lever 28 and the part 9 assume approximately the position shown in Fig. 2. The arms 10 also move upward with the part 9 and cease to embrace the ball 11, which latter however continues to be supported in position by the resilient pressure of the plunger 17 which holds the ball against the member 12 which is coaxial with the plunger 17. On the shock of impact the ball 11 is immediately dislodged from the position shown at Fig. 2 and falling clear to one side or the other of the members 12 and 17, assumes the position shown at Fig. 3. The plunger 17 is thus released and immediately moving upward it carries the detonator 24 with it into contact with the striker 26, thus firing the grenade. By increasing the strength of the spring which acts on the plunger 17 so that the ball is held in position with sufficient pressure to prevent its displacement even under the influence of a violent shock, the safety cage 9 might in certain cases be dispensed with. In such cases the member 12 may also be made movable and be spring controlled, the arrangement being such that immediately the safety lever is released by the grenade being thrown, the pressure exerted by the spring or springs is partially relaxed to an extent that will allow the ball to be displaced by a shock of impact of sufficient magnitude.

It will be seen that the firing mechanism cannot operate until the safety lever is released, thus obviating the danger which results from the liability of hand grenades as at present constructed exploding while in the hand of the thrower, as may happen, if, in the act of throwing the grenade, the hand of the thrower should come into contact with any object, for example the rear wall of a trench. It is also to be observed that by reason of the improvements the necessity of employing streamers to insure that the forward end of the grenade shall strike the ground, is avoided, since the aforesaid ball will be released and displaced immediately the grenade strikes the ground, thus obviating the well known disadvantages resulting from the use of these streamers.

In order to avoid liability of the ball be-

coming displaced by centrifugal action during the passage of the grenade through the air, the ball or member must be so situated that its center coincides for all practical purposes with the center of gravity of the grenade.

What we claim and desire to secure by Letters Patent of the United States is:—

1. A grenade comprising a pair of relatively movable members, means for causing said members to move toward each other, a firing mechanism controlled by the relative movement of said members, and a displaceable member supported between said relatively movable members and normally holding them apart, said member being displaced laterally from between said relatively movable members by shock of impact of the grenade.

2. A grenade comprising a pair of relatively movable members, means for causing said members to move toward each other, a firing mechanism controlled by the relative movement of said members, a displaceable member supported between said relatively movable members and normally holding them apart, said member being displaced laterally from between said relatively movable members by shock of impact of the grenade, and means for preventing displacement of said relatively movable members until after the grenade has been thrown.

3. A grenade comprising a pair of relatively movable members, means for causing said members to move toward each other, a firing mechanism controlled by the relative movement of said members, a displaceable member supported between said relatively movable members and normally holding them apart, said member being displaced laterally from between said relatively movable members by shock of impact of the grenade and a safety device for normally restraining said member from becoming displaced, and means for moving said safety device from its restraining position after the grenade has been thrown.

4. A grenade comprising a pair of relatively movable members, means for causing said members to move toward each other, a firing mechanism controlled by the relative movement of said members, and a ball supported between said relatively movable members and normally holding them apart, said ball being displaced laterally from between said relatively movable members by shock of impact of the grenade.

5. A grenade of the impact ignition type, comprising firing mechanism, a displaceable member, means for supporting said member in a position to render the firing mechanism inoperative until said member is displaced by shock of impact, a safety device for normally restraining said member from becom-

ing displaced, and a spring influenced lever controlling said safety device and liberated after the grenade has been thrown.

6. A grenade comprising a pair of relatively movables members, means for causing said members to move toward each other, firing mechanism controlled by the relative movement of said members, a displaceable member supported between said relatively

10 movable members and normally holding them apart, said member being displaced laterally from between said relatively movable members by shock of impact of the grenade and a slideable safety device for normally restraining said member from becoming displaced, and means for moving said slideable safety device from its restraining position after the grenade has been thrown.

7. A grenade of the impact ignition type, comprising firing mechanism, a spring controlled plunger forming part of the firing mechanism, a member located coaxially with said plunger, and a displaceable ball normally supported at or about the center of gravity of the grenade between said spring controlled plunger and said co-axial member with sufficient pressure to insure that the ball will become displaced to release the spring controlled plunger on shock of impact.

8. A grenade of the impact ignition type, comprising firing mechanism, a spring controlled plunger forming part of the firing mechanism, a member located co-axially with said plunger, a displaceable ball normally supported at or about the center of gravity of the grenade, between said spring controlled plunger and said co-axial member, with sufficient pressure to insure that the ball will become displaced to release the plunger on shock of impact, and means for preventing said ball from becoming displaced until after the grenade has been thrown.

9. A grenade of the impact ignition type, comprising firing mechanism, a spring con-

trolled plunger having a conical end and forming part of the firing mechanism, a co-axial member also having a conical end, a displaceable ball normally supported at or about the center of gravity of the grenade 50 between the conical ends of said plunger and co-axial member with sufficient pressure to insure that the ball will become displaced to release the said plunger on shock of impact.

10. A grenade of the impact ignition type, comprising firing mechanism, a spring controlled plunger having a conical end and forming part of the firing mechanism, a coaxial member also having a conical end, 60 a displaceable ball normally supported at or about the center of gravity of the grenade between the conical ends of said plunger and co-axial member with sufficient pressure to insure that the ball will become displaced to release the said plunger on shock of impact, a safety device for normally restraining said ball from becoming displaced, and means for moving said safety device from its restraining position after the grenade 70 has been thrown.

11. A grenade of the impact ignition type, comprising firing mechanism, a spring controlled plunger forming part of the firing mechanism, a member located coaxially with 75 said plunger, a displaceable ball supported at or about the center of gravity of the grenade between said spring controlled plunger and said co-axial member, and means whereby the spring pressure normally exerted on the ball by the plunger and co-axial member is rendered sufficient to prevent the ball from becoming displaced but is released to such an extent after the grenade has been thrown that the shock of impact will suffice 80 to cause the ball to be displaced and liberate the firing mechanism.
